(57) **CLAIM**

What is claimed is the ornamental design for a beverage dispenser, as shown and described.

DESCRIPTION

FIG. 1 is a perspective view of the beverage dispenser;
 FIG. 2 is a front elevational view thereof;
 FIG. 3 is a rear view thereof;
 FIG. 4 is a right side view thereof;
 FIG. 5 is a left side view thereof;
 FIG. 6 is a top plan view thereof; and,
 FIG. 7 is a bottom plan view thereof.
 The broken lines in the drawing depict portions of the
 beverage dispenser that form no part of the claimed design.
